UNITED STATES PATENT OFFICE.

CHARLES F. POWELL, OF UTICA, OHIO.

SHOE-SHINER.

968,191.

Specification of Letters Patent. Patented Aug. 23, 1910.

Application filed May 24, 1910. Serial No. 563,149.

To all whom it may concern:

Be it known that I, CHARLES F. POWELL, a citizen of the United States, residing at Utica, in the county of Licking and State 5 of Ohio, have invented a new and useful Shoe-Shiner, of which the following is a specification.

It is the object of this invention to provide in a simple, merchantable and inexpensive form, a platform upon which the 10 foot of the operator may be rested, said platform having elements along its remote edges, adapted to receive a polishing strip, which, being passed across the shoe of the 15 operator, may be reciprocated thereon to polish the same.

Another object of the invention is to provide a shoe shining device, adapted, at once, to be employed in the manner above specified, 20 and to be folded together to serve as a holder in which polishing material may be mounted, whereby the device may be employed as a shoe brush.

In the drawings, Figure 1 shows the device 25 in perspective, positioned as a platform upon which the foot of the operator may be mounted for polishing the shoe; Fig. 2 is a transverse section, the view illustrating the manner in which the device may be operated 30 to polish the shoe; Fig. 3 is a perspective showing the component parts of the platform folded together, so that the device may be used as a shoe brush, parts being broken away; and Fig. 4 is a transverse 35 section of the device when the same is disposed as shown in Fig. 3.

In carrying out the invention a platform 1 is provided, the same being a box like structure. This platform 1 is provided 40 along its remote, longitudinal sides, with guides 2, straight in their intermediate portions and spaced apart from the platform 1 to receive rollers 3.

As shown in Fig. 2, the foot of the operator 45 may be rested upon the platform 1 and a polishing strip 4 may be threaded through the guides 2, and extended across the shoe of the operator. Obviously, when the polishing strip 4 is reciprocated, the shoe of 50 the operator will be rubbed by the strip, the rollers 3 permitting the strip to move anti-frictionally upon the guides 2.

The platform 1 is longitudinally divided, as indicated at 5, into two similar parts 6, these parts being hingedly connected as 55 shown at 7. When desired, the parts 6 may be swung transversely together, as shown in Fig. 3, to position the guides 2 in close proximity to each other, so that they may be grasped simultaneously by the hand of the 60 operator. Into the open ends of the parts 6, when disposed as shown in Fig. 3 polishing material of any desired form may be thrust. This polishing material, preferably, although not necessarily, may be the 65 strip 4. When the device is disposed as shown in Figs. 3 and 4 it may be employed as a shoe brush for cleaning and for polishing.

When the device is positioned as shown in 70 Fig. 1 the parts 6 serve to define a compartment 8 in which the polishing strip 4, the blacking box, the dauber and the like may be housed.

The advantages incident to the structure 75 herein disclosed are that when the body of the shoe alone needs to be polished, the device may be employed as shown in Fig. 2. When it is desired to polish the top, the device may be positioned as shown in Figs. 3 80 and 4, whereupon the top may be polished in the usual manner, thus, a person wearing high shoes or boots, may, by disposing the device as shown in Fig. 2, give the body portion of the foot wear occasional touches, and, 85 upon occasions, likewise polish and clean the tops of the shoes or the legs of the boots, the entire operation being carried forward with a single implement; it being unnecessary to use the polishing platform to shine the 90 lower portion of the foot wear, and subsequently to employ another separate brush for polishing the tops of shoes or the legs of boots.

Having thus described the invention, what 95 is claimed is:—

A shoe shining device consisting of a box-like platform having guides disposed upon its remote sides, through which guides a polishing strip may be passed to engage a 100 shoe which is rested upon the platform, the platform being longitudinally divided into two similar, hingedly connected parts, adapted to be swung together, to position

the guides side by side to serve as a handle and to position the component parts of the platform side by side to form an open-bottomed casing, to receive polishing material
5 whereby the device may be used as a shoe brush.

In testimony that I claim the foregoing

as my own, I have hereto affixed my signature in the presence of two witnesses.

CHARLES F. POWELL.
